(57) **CLAIM**

The ornamental design for a brush with cover, as shown and described.

DESCRIPTION

FIG. 1 is an isometric view of a top and side of an ornamental design for a brush with cover;

FIG. 2 is a side elevational view of the brush with cover of FIG. 1, the other sides being identical thereto;

FIG. 3 is a top plan view of the brush with cover of FIG. 1; FIG. 4 is a bottom plan view of the brush with cover of FIG. 1;

FIG. 5 is an isometric view of a top and side of another ornamental design for a brush with cover;

FIG. 6 is a side elevational view of the brush with cover of FIG. 5, the other sides being identical thereto;

FIG. 7 is a top plan view of the brush with cover of FIG. 5; FIG. 8 is a bottom plan view of the brush with cover of FIG. 5;

FIG. 9 is an isometric view of a top and side of still another ornamental design for a brush with cover;

FIG. 10 is a side elevational view of the brush with cover of FIG. 9, the other sides being identical thereto;

FIG. 11 is a top plan view of the brush with cover of FIG. 9;

FIG. 12 is a bottom plan view of the brush with cover of FIG. 9;

FIG. 13 is an isometric view of a top and side of yet another ornamental design for a brush with cover;

FIG. 14 is a side elevational view of the brush with cover of FIG. 13, the other sides being identical thereto;

FIG. 15 is a top plan view of the brush with cover of FIG. 13; and,

FIG. 16 is a bottom plan view of the brush with cover of FIG. 13.

The dash-dash-dash lines are for the purpose of illustrating portions of the article that form no part of the claimed design. The dash-dot-dash lines form no part of the claimed design and represent a boundary line.

1 Claim, 12 Drawing Sheets
